UNITED STATES PATENT OFFICE.

ARTHUR F. HUNTINGTON, OF PORTSMOUTH, VIRGINIA.

BUSHING TOOL.

Application filed March 31, 1922. Serial No. 548,414.

To all whom it may concern:

Be it known that I, ARTHUR F. HUNTINGTON, a citizen of the United States, residing at Portsmouth, in the county of Norfolk and 5 State of Virginia, have invented new and useful Improvements in Bushing Tools, of which the following is a specification.

My present invention has reference to a simple means for inserting a bushing in 10 the eye ends of springs of automobiles or similar vehicles without necessitating the removal of the springs from the vehicles.

A further object is to produce a device 15 of this character which shall be of an extremely simple construction, cheaply manufactured and marketed, readily applied, easily and quickly operated, and thoroughly efficient in operation.

The foregoing, and other objects which 20 will appear as the nature of the invention is better understood, may be accomplished by a construction, combination and operative association of parts, such as is disclosed by the drawings which accompany and 25 which form part of this specification.

In the drawings:—

Figure 1 is a view illustrating the application 30 of the improvement.

Figure 2 is a plan view of the improvement on an enlarged scale.

Figure 3 is a sectional view on the line 35 3—3 of Figure 2.

Figure 4 is a sectional view on the line 4—4 of Figure 2.

Figure 5 is a sectional view on the line 45 5—5 of Figure 2.

As disclosed in Figure 1 of the drawings, it is merely necessary to jack up the end 50 of a vehicle when a bushing is to be applied to the springs thereof in accordance with this invention. The old bushing may be removed. The vehicle is jacked up only at the ends thereof in which bushings are to be applied. The spring shackle bolt is removed from the springs which allows the 55 spring to drop clear of the spring support or shackle. One side of the old bushing is cut with a hack saw and is forced out of the eye of the spring by a hammer and punch. When this is accomplished, my improvement is slid over the end of the spring to arrange the head on the screw thereof in a line with the bushing.

My improvement includes a substantially 55 U-shaped frame 1, the parallel arms of which, at their outer ends are preferably

thickened and bifurcated. In the bifurcated ends there is received a plate 2, suitable removable pivots 3, preferably in the nature of short bolts being screwed through openings in the said ends of the frame and through openings in the ends of the head plate 2. The connecting element for the arms of the yoke is, for distinction, indicated by the numeral 4, the same having a central opening 5 therethrough and through reduced openings 6 to the sides of the said opening 5. Through the central opening 5 there is passed the non-threaded end 7 of a screw 8. The screw has on its outer end 70 a head 9 provided with a transverse opening through which passes a handle bar 10 having one of its ends integrally formed with a head 11 and its other end provided with a removable head 12. The end of the screw 75 opposite that provided with the head 9 has a ball end 13 and an annular groove 14 inward of the said ball. The ball end is designed to be received in a cup-shaped depression in a boss 15 on the inner face of a 80 disk-like head 16, while passing through the boss and received through the groove 14 are the arms of a cotter pin 17.

The element 2 which I have termed the end plate for the frame 1 is really in the 85 nature of a disk, being rounded in plan and having its ends provided with extensions through which the sustaining elements 3 pass.

The threads of the screw 8 are received 90 through the threaded bore of a collar 18, the same being provided with a flange 19. The flange has threaded openings in which are screwed the ends of bolt members 20, the shanks of the said bolts passing through 95 the openings 6 in the element 4 of the head. Between the heads of the bolt and the element 4 of the frame there are arranged upon the shanks of the said bolts springs 21. This permits of the screw 8 being 100 bodily moved for a determined length through the element 4 of the frame 1, so that a pounding action may be delivered by the disk-like head 16 against one end of the bushing, it being understood that the head 105 2 of the frame is arranged in contact with the eye of the spring opposite the end thereof in which the bushing is inserted. By turning the screw, the head 16 will exert a pressing force against the end of the bushing, the head being swivelly mounted on the screw is, of course, rotatable therewith.

The bushings can be easily and quickly inserted in the eyes of springs with the improvement, and it is thought that the foregoing description, when taken in connection with the drawings will fully set forth the construction, operation and advantages of the device to those skilled in the art to which such inventions relate.

Having described the invention, I claim:—

10 1. In a device for the purpose set forth, a substantially U-shaped frame having a removable end and a screw freely received through its other end, a swiveled head on the inner end of the screw, a handle slidable through the opposite end of the screw, a threaded sleeve in the frame engaged by the screw, spring means holding the sleeve in contact with the end of the frame and preventing the turning of the sleeve on the

frame, and said means permitting a limited 20 longitudinal sliding movement of the screw through the frame.

2. In a device for the purpose set forth, a substantially U-shaped frame, a disk removably and hingedly connected to the arms 25 at the open end of the frame, a screw slidable through the closed end of the frame, an operating handle for the screw, a disk-like head swiveled on the end of the screw, a sleeve having a threaded bore engaged by 30 the threads of the screw, spaced elements on the sleeve passing through the closed end of the frame, and spring means influencing said elements to hold the sleeve in contact with the frame, as and for the purpose set 35 forth.

In testimony whereof I affix my signature.

ARTHUR F. HUNTINGTON.
